United States Patent Office

Des. 197,617
Patented Mar. 3, 1964

197,617

CASE FOR A CLOCK OR THE LIKE

Victor Shanok and Jesse P. Shanok, both of
863 65th St., Brooklyn, N.Y.

Filed Jan. 8, 1962, Ser. No. 68,220

Term of patent 14 years

(Cl. D42—7)

FIG. 1

FIG. 2

FIG. 3

FIG. 4

FIG. 5

FIG. 6

FIGURE 1 is a front elevational view of a case for a clock or the like showing our new design;

FIGURE 2 is a side elevational view thereof;

FIGURE 3 is a top plan view thereof;

FIGURE 4 is a rear elevational view thereof;

FIGURE 5 is a bottom view thereof; and

FIGURE 6 is a cross-section of FIGURE 4 taken along line 6—6 thereof.

We claim:

The ornamental design for a case for a clock or the like, substantially as shown.
